APPARATUS FOR DRAINING BUNDLES OF SHINGLES AND THE LIKE

Filed Nov. 26, 1928 2 Sheets-Sheet 2

UNITED STATES PATENT OFFICE

HARRY E. GOSCH, OF NORTH TONAWANDA, NEW YORK, ASSIGNOR TO CREO-DIPT COMPANY INC., OF NORTH TONAWANDA, NEW YORK, A CORPORATION OF NEW YORK

APPARATUS FOR DRAINING BUNDLES OF SHINGLES AND THE LIKE

Application filed November 26, 1928. Serial No. 321,853.

This invention relates to an apparatus for draining bundles of shingles which have been dipped in a bath of liquid, such as a liquid stain, paint or preservative, for the purpose of removing the excess liquid therefrom before the bundles of shingles are used or put on the market, and thereby facilitate drying of the shingles as well as saving the excess liquid for use in treating subsequent bundles.

An apparatus of this character is shown in application for United States patent, filed May 3, 1928, Ser. No. 278,783. The present invention is an improvement on this prior construction.

In the use of this earlier apparatus it is found that when starting and stopping the rotary movement of the cage, reel or skeleton drum in which the bundles of shingles were whirled so as to remove the excess liquid therefrom by centrifugal action, during the beginning of this rotary action and also during the last part of this rotary action after completing the draining of the bundles, the latter tended to chuck excessively from one side of the rotary cage or drum to the other, thereby not only setting up an unnecessary vibration and strain upon the machine, but also causing the two tiers of shingles at opposite ends of the bundles to be driven toward each other excessively with a hammering or pounding action and thereby at times cause the binder around the waist or central part of the bundles to be broken so that the shingles would be scattered or spilled.

This chucking action of the bundles within the rotary cage or drum does not occur during the intermediate part of the rotary action of the same while it is running at full speed inasmuch as at this time centrifugal force is sufficiently strong to hold the bundles firmly against one side of the cage instead of permitting them to chuck from one side of the cage to the other, which takes place only during the beginning and stopping of the operation while rotating at comparatively slow speed.

It is the object of this invention to provide simple and efficient means whereby the bundles of shingles within the rotary cage

may be conveniently fastened or held against displacement within the cage so that chucking of the bundles may be prevented, particularly at the time of beginning and ending of the draining operation when this is necessary.

In the accompanying drawings:—

Figure 1 is a vertical longitudinal section of a satisfactory form of my invention embodied in a draining apparatus.

Figure 2 is a side elevation of the apparatus with the enclosing hood or casing removed from the cage so as to expose the latter.

Figure 3 is a vertical section, on an enlarged scale, of the valve mechanism and adjacent parts of the motor whereby the clamping jaw is shifted and showing this valve mechanism in a position different from that represented in Fig. 1.

Figure 4 is a longitudinal section taken on line 4—4 Fig. 3.

Similar characters of reference indicate like parts in the several figures of the drawings.

The draining apparatus itself may be variously constructed to suit the particular form of bundles of shingles or other materials which are to be drained of their excessive liquid which may adhere thereto after the same have been dipped or otherwise coated, but the apparatus which is shown in the drawings as an example, consists generally of a rotary cage, reel or skeleton drum which turns about a horizontal axis. As there shown, this cage comprises two vertical heads 10, 11 arranged at opposite ends of the cage, two longitudinal closed walls which are arranged on diametrically opposite sides of the axis of the cage and each consisting of a plurality of longitudinal spaced-apart bars 12 which connect the corresponding edges of the two heads 10, 11, and two open-work gates 13, 13 which are arranged on diametrically opposite sides of the cage but in planes at right angles to the walls formed by the fixed bars 12, 12, each of said gates being movable horizontally into and out of its operative position across one side of the cage for the purpose of permitting the bundles of shingles 14 which have been dipped in liquid

stain, paint or the like, to be introduced into the cage preparatory to draining the excess liquid therefrom and also to be removed from this cage after the draining operation has been completed.

5 A rotary cage is thus formed which is substantially square or rectangular in cross section and into the interior of this cage the bundles 14 to be drained are placed with the 10 two intercalated tiers of shingles facing the bars 12 of the cage while the binder 15 around the central parts of these bundles are arranged near the axis of the cage. The diameter of the cage between the two walls formed 15 by the two sets of walls 12 is less than the length of the bundles when the latter are put into the cage, so that when the bundles rest at one end on the bottom of the cage the opposite ends thereof 20 are spaced apart from the companion longitudinal top wall, as shown in Fig. 1.

For convenience in introducing the bundles into the cage and removing the same therefrom, a plurality of rollers 16 are arranged 25 on the inner side of the cage lengthwise of the two sets of bars 12 so that either of these two sets of rollers may form a support for the ends of the bundles which are lowermost and thereby permit them to be readily moved 30 into and out of the cage.

Each of the heads 10 and 11 preferably consists of a central hub 17, a plate 18 arranged on the inner side of this hub, and a plurality of cross bars 19 secured to this hub 35 and plate and also to the adjacent ends of the longitudinal bars 12 forming the respective longitudinal walls of the cage. The plate 18 of one of the heads is preferably made imperforate as shown at the right of Fig. 1, which plate will be hereafter referred to as the front plate, while the other plate 18 is provided with a central opening 20 and will be hereafter referred to as the rear plate.

The hub 17 of the front head is provided 45 with an outwardly projecting trunnion 21 which is journaled in a bearing 22 formed at the upper end of a standard 23 rising from the base 24 of the main frame, this trunnion being preferably extended so that in effect it 50 forms a part of the driving shaft 25 of the machine, which latter is additionally journaled at its outer end in a bearing 26 rising from a standard 27 on the main frame. The hub on the rear head of the cage is provided 55 with an outwardly extending trunnion 28 which is axially in line with the front trunnion 21 and journaled in a bearing 29 at the upper end of a standard 30 rising from the base 24 of the frame.

60 Motion is transmitted to the cage for rotating the same by means of a belt 31 passing around a driving pulley 32 on the shaft 25, or any other suitable means and this rotary movement of the cage may be controlled and 65 the cage may be also held against rotation

while being loaded and unloaded by a retaining device which preferably consists of a brake drum 33 mounted on the driving shaft, and a brake band 34 which may be either tightened or loosened relative to the periphery of the brake drum 33 by means of a hand lever 35 or any other suitable means.

As the cage or skeleton reel which contains the bundles is rotated the excess liquid is thrown off from these bundles by centrifugal force and discharged through the openings between the openwork sides of the cage into a suitable receptacle provided for this purpose. The means provided for this purpose consist of a pan 36 arranged below the cage and a 80 vertically movable hood or casing 37 adapted to enclose the top, lateral sides and ends of the cage so as to catch the excess liquid which is thrown off from the bundles and direct the same into the pan 36, from which latter this liquid is conducted into the tank where the same is utilized for dipping further bundles which are to be treated.

In the absence of any provision to prevent it, the bundles if left loose within the cage, 90 would, during the initial part of the rotary movement of the cage and also the final portion of this movement when the drainage is completed, move back and forth crosswise of the cage with a chucking action due to the 95 comparatively slow rotary motion of the cage at this time.

This chucking effect upon the bundles is 100 objectionable inasmuch as it drives the shingles inwardly from their outer ends so that the inner ends thereof overlap to a greater extent and therefore are liable to split the binders which hold the bundles together at the waist due to the wedging effect of the shingles.

105 After the cage has acquired its normal or maximum rotary speed centrifugal force operates to hold the bundles in their outermost radial position against one wall of the cage so that this chucking action of the bundles does not occur at this time. In order to prevent chucking of the bundles during the initial and final portions of rotation of the cage, means are provided for holding the bundles against displacement during these periods, 110 which means, as shown in the drawings, are preferably constructed as follows:

The numeral 37 represents a clamping jaw 115 which preferably has the form of a disk and is adapted to engage with the rear side of the rearmost bundle of a group arranged within the cage while the front side of the foremost bundle of this group is engaging with the plate 18 of the front head of the cage. This 120 jaw 37 is movable into and out of the cage through the opening 20 in the plate 18 of the rear head so that this jaw may be withdrawn from the interior of the cage and permit free introduction of the bundles into the cage and removal therefrom. As shown by full lines 125 130

this jaw is withdrawn through the opening 20 so that it does not obstruct the path of the bundles, while in dotted lines the same is engaged with the rear side of the rearmost bundle while the clamping mechanism is in operation.

This clamping jaw is moved into and out of its operative position by means of a piston 38 which reciprocates in a cylinder 39 formed in the outer end of the rear trunnion 28, and a piston rod 40 which connects this piston and the clamping jaw 37 and slides axially through the inner part of the trunnion 28, as shown in Fig. 1.

The piston 38 is pushed inwardly by compressed air or other fluid so as to engage the clamping jaw 37 with the rear end of the series of bundles to be drained, and the outward movement of this piston is effected by the suction of a vacuum apparatus.

The means whereby fluid under pressure is admitted into the outer end of the cylinder 39 for forcing the piston inwardly and also exhausting the air from the outer end of this cylinder for causing the piston to be moved outwardly and the clamping jaw to be disengaged from the shingles, are preferably constructed as follows:

The numeral 41 represents a communicating pipe through which the compressed air is supplied to the outer end of the cylinder and the spent air is exhausted therefrom, which transfer pipe is stationary but connected with the outer end of the cylinder 39 by means of a rotary pipe coupling so as to permit the cage to turn and still maintain a connection at all times between the outer end of the motor cylinder 39 and the means which connect the same with the pressure supply and the exhaust devices. This rotary coupling may be variously organized, but as shown in Figs. 1 and 3, the same comprises a central coupling nipple 42 extending axially through the head 43 secured to the outer end of the cylinder 39, and a stuffing box 44 whereby an air-tight joint is formed between this head 43 and the coupling nipple 42, the latter being provided at its inner end with a collar 45 which engages with the inner side of the head 43.

By these means compressed air may be admitted to the outer end of the cylinder 39 for pushing the cylinder inwardly and engaging the clamping jaw with the bundles of shingles and upon exhausting this air the piston is moved outwardly and the clamping jaw is released from the bundles of shingles. Inasmuch as the clamping of the bundles of shingles so as to guard against chucking of the same is only necessary during the initial part of the rotary movement and also the final part of this rotary movement of the cage, means are provided which will permit the attendant to put the clamping mechanism in operation manually but which will

operate automatically to release the clamping or holding means from the bundles after a comparatively short time, and thereby permit the bundles of shingles to assume a definite position under centrifugal action within the draining cage and retain this position without further change during the operation of draining the same.

The preferred form of mechanism for thus manually clamping the bundles of shingles and then automatically releasing the same is effected by a timed or slow-acting release device which is preferably constructed as follows:

The numeral 46 represents a valve casing so provided with a cylindrical bore 47 forming the valve seat of a cylinder or plunger valve 48 which is adapted to slide lengthwise in this seat 47. On diametrically opposite sides of the inner part of the casing 46 the same is provided with inlet and outlet pressure ports 49, 50. The central part of this casing is provided on opposite sides with inlet and outlet vent ports 51, 52 and on the upper part of this casing the same is provided on opposite sides with inlet and outlet exhaust ports 53, 54. The outlet ports 50, 52 and inlet port 53 communicate by a communicating chamber 55 with the pipe 41, the inlet pressure port 49 is connected by means of a pipe 56 with an air compressor or other means for supplying fluid pressure, the inlet vent port 51 leads to the atmosphere and the outlet port 54 is connected by means of a pipe 57 with an air exhausting device of any suitable character capable of creating a vacuum. The plunger or piston valve 48 is provided with a coupling port 58, which upon moving this valve into its innermost position, as shown in Fig. 3, will place the inlet and outlet ports of the pressure line in communication with each other. Upon moving this piston valve outwardly into its central position, as shown by dotted lines in Fig. 3, the coupling port 58 thereof will establish connection between the inlet and outlet vent ports 51, 52 and upon moving this piston or plunger into its outermost position, as shown by full lines in Fig. 1, the coupling port 58 thereof will connect the inlet and outlet ports 53, 54 of the exhaust line.

When, therefore, the piston valve 48 connects the cylinder 39 with the air pressure line, the motor piston 38 will be pushed inwardly and produce a clamping action on the bundles of shingles. Upon moving the piston valve into its central position the cylinder 39 will be placed in communication with the atmosphere and thereby relieve and the pressure of the clamping jaw against the bundles in the cage, and by moving the piston valve into its outermost position the cylinder 39 will be placed in communication with the suction line for creating a vacuum in this cylinder and causing the piston 38

to be withdrawn from the bundles of shingles into its outermost position in which the jaw 37 clears the path of the same, as shown by full lines in Fig. 1.

5 The depression of the piston valve 48 is produced by a handle 59 which is secured to the outer end of a valve stem 60 connecting the piston valve with the handle and passing through a stuffing box 61 at the front of the 10 valve casing 46 and the outward movement of this piston valve is produced by a spring 62 surrounding the valve stem and bearing at its inner end against the stuffing box 61 and its outer end against the handle 59, as shown in 15 Fig. 3.

The depression of the valve 48 into its innermost position can be effected very easily and quickly by pressure of the hand against the handle 59, but the backward, return or 20 outward movement of the same is retarded by means of a checking or retarding device which preferably consists of a check valve 63 arranged within a pocket 64 on the lower end of the valve casing 46 and adapted to close 25 inwardly against a valve seat 65 which controls a retarding port leading to the inner or lower end of the valve bore 47. This check valve is yieldingly held against its seat by means of a spring 66 arranged within the 30 pocket 64 and interposed between the outer side of the valve 63 and a screw cap 67 applied to the lower end of the casing 46, this cap being provided with an opening 68 whereby this pocket communicates with the atmosphere. 35 The casing 46 of the controlling valve is held stationary in any suitable manner, for instance by a bracket 69 connecting the same with the adjacent bearing 29, as shown in Fig. 1.

40 Upon depressing the plunger valve 48 the check valve 63 opens freely and permits the air below the plunger to escape from the lower end of the bore 47, but during the upward stroke of the plunger valve 48 the check valve 45 63 will engage the seat 65 and almost close the same, sufficient leakage being permitted in this check valve so that only a slow passage of air from the exterior of the casing will be possible into the lower end of the valve bore 47 as the plunger valve rises, and thereby causing the upward or outward movement of this plunger valve to be retarded.

It follows from this construction that after the compressed air is admitted to the cylinder 39 for forcing the jaw 37 against the bundle of shingles and then removing the hand pressure from this plunger valve, that this air pressure will be maintained on the jaw 37 for a short time, which is, however, of sufficient duration to permit the draining cage after starting its rotation, to get under full or normal speed, and thereafter the coupling port of the plunger valve 48 during its continued upward or outward movement at a slow rate will first cut off the compressed

air supply, then connect the working end of the cylinder 39 with the atmosphere through the vent ports 51, 52, and then connect this end of the working cylinder with the exhaust ports 53, 54 for withdrawing the clamping 70 jaw from the bundles of shingles. As a result of this slow release of the clamping mechanism from the bundles the latter will be reliably held against radial displacement in the draining cage during the initial slow rotary movement of the latter when starting the draining operation, and when the cage has acquired a sufficient rotary speed so that the bundles therein will be held by centrifugal force against one side only of the draining cage, the bundles are released from the grip of the clamping device, thereby permitting the bundles to adjust themselves automatically to the inner surface of the cage in response to the centrifugal force acting thereon and enabling them to spread out or relax into a loose condition so that the excess liquid deposited thereon during the dipping process will be able to escape therefrom with the maximum freedom and thus insure the most effective draining of the bundles and recovery of the greatest amount of the liquid with which the bundles have been treated. 80

After the draining cage has been rotated a sufficient length of time to drain the surplus liquid from the bundles of shingles and just before the power for turning the draining cage is cut off, the attendant pushes the plunger valve 48 inwardly so as to again admit compressed air into the working end of the motor cylinder 39 for the purpose of clamping or holding the bundles within the draining cage against displacement as the rotary speed of the draining cage gradually slows up and the cage finally comes to rest, thereby preventing the bundles from chucking radially from one side of the cage to the other as the rotary speed of this cage is reduced below normal, thereby preventing the two groups of shingles in each bundle from 100 being hammered or pushed in endwise, whereby the shortening of the bundle and possible breaking of the binders and scattering of the shingles is prevented. 110

The operation of this controlling valve is 115 preferably so timed that the clamping action of the jaw 37 on the bundles is not released until after the rotary action of the draining cage ceases. Thereafter the slow returning plunger valve 48 under the action of the spring 62 will successively cut off the air pressure from the working cylinder 39, then connect this cylinder with the vent to the atmosphere, and then connect the same with the suction line 57 so as to withdraw the clamping jaw 37 from the space within the cage, leaving the latter unobstructed and permit the removal of the draining bundles from the cage and the loading of a new batch of 130

bundles into the same without any interference from the clamping mechanism.

I claim as my invention:—

1. An apparatus for draining bundles of shingles and the like dipped in liquid, comprising a rotary cage adapted to receive said bundles, and means for holding said bundles against displacement in said cage including a clamping jaw adapted to engage against the side of the bundles, and means for shifting said jaw including a pneumatic cylinder, a piston adapted to be reciprocated by air pressure in said cylinder, a rod connecting said piston and jaw, and a controlling device for admitting air under pressure quickly into said cylinder and automatically exhausting the same slowly therefrom.

2. An apparatus for draining bundles of shingles and the like dipped in liquid, comprising a rotary cage adapted to receive said bundles, and means for holding said bundles against displacement in said cage including a clamping jaw adapted to engage against the side of the bundles, and means for shifting said jaw including a pneumatic cylinder, a piston adapted to be reciprocated by air pressure in said cylinder, a rod connecting said piston and jaw, and a controlling device for admitting air under pressure quickly into said cylinder and exhausting the same slowly therefrom, comprising a valve casing having a chamber communicating with said cylinder, a pressure port connected with a compressed air supply and an exhaust port connected with an air exhausting device, and a valve movable in said casing and adapted when in its inner position to connect said communicating chamber with said pressure port and when in its outer position to connect said transfer port with said exhaust port.

3. An apparatus for draining bundles of shingles and the like dipped in liquid, comprising a rotary cage adapted to receive said bundles, means for holding said bundles against displacement in said cage including a clamping jaw adapted to engage against the side of the bundles, means for shifting said jaw including a pneumatic cylinder, a piston adapted to be reciprocated by air pressure in said cylinder, and a rod connecting said piston and jaw, and a controlling device for admitting air under pressure quickly into said cylinder and exhausting the same slowly therefrom, comprising a valve casing having a chamber communicating with said cylinder, a pressure port connected with a compressed air supply and an exhaust port connected with an air exhausting device, a valve movable in said casing and adapted when in its inner position to connect said communicating chamber with said pressure port and when in its outer position to connect said transfer port with said exhaust port, a spring for moving said valve outwardly, and a check valve which permits the air to escape from

the inner end of said casing upon moving the valve inwardly but retards the admission of air in the inner end of said casing upon moving the valve outwardly.

4. An apparatus for draining bundles of shingles and the like dipped in liquid, comprising a rotary cage adapted to receive the bundles to be drained, and means for holding said bundles against displacement in said cage including a clamping jaw adapted to engage the bundles, and a shifting means connected with said jaw and movable lengthwise and co-axially with the axis of said cage.

5. An apparatus for draining bundles of shingles and the like dipped in liquid, comprising a rotary cage adapted to receive the bundles to be drained, means for rotatably supporting said cage including a trunnion arranged at one end of the cage and journaled in a bearing, and means for holding the bundles against displacement including a clamping jaw adapted to engage the bundles, and a shifting rod connected with said jaw and slidable lengthwise in said trunnion.

6. An apparatus for draining bundles of shingles and the like dipped in liquid, comprising a rotary cage adapted to receive the bundles to be drained, means for rotatably supporting said cage including a trunnion arranged at one end of the cage and journaled in a bearing, and means for holding the bundles against displacement including a clamping jaw adapted to engage the bundles, a shifting rod connected with said jaw and slidable lengthwise in said trunnion, a cylinder arranged on said trunnion, a piston arranged in said cylinder and connected with said rod, a pipe adapted to supply compressed air to said cylinder and deliver air therefrom, and a rotary joint connecting said pipe with said cylinder.

7. An apparatus for draining bundles of shingles and the like dipped in liquid, comprising a cage adapted to receive the bundles and rotatable about a horizontal axis, one end of said cage having a head forming an abutment for the bundles and the other end of the cage having a head provided with a central opening, and means for pressing said bundles against said abutment including a clamping jaw adapted to engage the bundles and movable through said opening, and means for shifting said jaw including a rod connected with said jaw and slidable lengthwise of the axis of the cage.

8. An apparatus for draining bundles of shingles and the like comprising a rotary cage adapted to receive the bundles, and means for holding said bundles against movement in said cage, comprising a clamping jaw adapted to engage the bundles, a motor having a cylinder and a piston arranged in the cylinder and connected with the jaw, and a valve for connecting said cylinder with a pressure medium, or venting the same to the

atmosphere, or connecting the same with an exhausting device.

9. An apparatus for draining bundles of shingles and the like, comprising a rotary cage adapted to receive said bundles, and means for holding said bundles against displacement in said cage including a jaw engageable with said bundle and means for transmitting motion to said jaw from the exterior of said cage including a shifting element movable lengthwise and co-axially with the axis of said cage.

In testimony whereof I hereby affix my signature.
